UNITED STATES PATENT OFFICE.

ERCOLE CAVICCHI, OF QUINCY, MASSACHUSETTS.

GRINDING OR POLISHING MACHINE.

1,312,235.

Specification of Letters Patent.

Patented Aug. 5, 1919.

Original application filed November 22, 1915, Serial No. 62,755. Divided and this application filed July 15, 1918. Serial No. 244,866.

To all whom it may concern:

Be it known that I, ERCOLE CAVICCHI, a citizen of the United States, and resident of Quincy, county of Norfolk, State of Massachusetts, have invented an Improvement in Grinding or Polishing Machines, of which the following description, in connection with the accompanying drawing, is a specification, like characters on the drawing representing like parts.

This invention relates to improvements in grinding or polishing machines of the type in which a rotary grinding or polishing member is pushed backward and forward over the surface to be polished such as marble, mosaic, terraza or other composition flooring and comprises certain improvements disclosed in my prior Patent No. 1,126,615, granted October 26, 1915, and is a division of my pending application Serial No. 62,755, filed November 22, 1915.

The present invention like that disclosed in my prior patent aforesaid comprises a rotary grinding head having a plurality of abrasive members adapted to rest upon the surface to be ground, said head being actuated by a motor preferably an electric motor.

The motor rests upon a platform which is supported at one end by the rotary grinding head and at the other end by a pair of wheels. In my prior patent aforesaid means are provided for supporting a weight directly over the grinding head in order to press the same firmly against the surface being ground, thereby increasing the efficiency of the tool.

One of the objects of the present invention is to so construct the machine that a greater portion of the weight of the motor is carried by the grinding head thereby greatly increasing the normal pressure of the grinding means upon the surface being treated.

In the use of grinding machines of this character it is desirable that the machine should be so constructed that it may be operated as far into the corners of the room as possible and also that it may be turned around in a relatively small space.

Another object of the invention therefore is to construct the machine so that it will be as compact as possible.

Another object of the invention is to construct a machine in such a manner that the wheels and the rotary grinding tool shall be

arranged to form a triangular support for the motor whereby the grinding tool will always sustain the same amount of weight of the motor irrespective of the unevenness of the surface being ground, the grinding tool itself having a triangular arrangement of grinding members whereby the pressure upon each grinding member will be maintained uniform notwithstanding the unevenness of the surface being treated.

Another object of the invention is to provide a novel form of driving mechanism which will enable the vertical shaft which actuates the grinding tool to be carried beneath the motor.

Another feature of the invention consists in so constructing the casing for the gearing through which the motor drives the grinding tool that it may be quickly and readily dismantled for the purpose of cleaning or replacement.

A further feature of the invention consists in providing a novel dust proof casing for said gearing.

Other objects and features of the invention will more fully appear from the following description and accompanying drawings and will be pointed out in the annexed claims.

In the drawings;

Figure 1 is a vertical longitudinal section of the grinding and polishing machine embodying a preferred form of my invention the motor and certain shafts being shown in elevation.

Fig. 2 is a plan view of the machine, the motor having been removed.

The grinding and polishing machine illustrated herein comprises a platform 1 in the form of a casting having stands 2 adapted to support an electric motor 3. The casting forming the platform preferably is so constructed as to provide a casing for the gears which actuate the grinding tool and also provide journals for the necessary shafts. As illustrated in Fig. 1 the central portion of the platform casting has a downwardly offset portion 4 which provides a casing for a gear 5 which actuates the shaft 6 which drives the rotary grinding head 7. This downwardly offset portion of the casting also comprises a boss 8 which forms a journal for the shaft 6. The forward portion of this offset extension merges into a

semi-annular casing 9 which incloses a gear 10 rotatable about a stud shaft 11 which is journaled at its outer end in a thickened boss 12 at the upper central portion of said 5 casing 9. The members of the platform 1, the downwardly offset casing 4, the boss 8, the casing 9 and the boss 12 preferably are integral, thus forming a very rigid structure. The opposite end of the shaft 11 is secured 10 in a socket 13 in the central portion 14 of a cover 15 for the casing 4 which is of generally circular form but provided with extensions or ears 17 and 18 by which it is secured to the platform by suitable bolts 19. 15 The central portion 14 of the cover is provided with a downwardly extending boss which forms a socket or bearing for the upper end of the shaft 6, suitable antifriction means such as disks 16 being provided 20 to form a thrust bearing.

The shaft 11 is secured in the socket 13 by a set screw 20 or in any other suitable manner and has rotatably mounted upon it a beveled gear 21 which engages the gear 5. 5 The beveled gear 21 has an extended hub 22 upon which the hub 23 of the gear 10 is secured by a key 24. The gear 10 engages a gear 25 of smaller diameter which is secured upon the shaft 26 of the electric 30 motor 3. It will be obvious that the rotation of the shaft 26 will cause the gear 25 to drive the gear 10 thereby rotating the beveled gear 21 which in turn will rotate the gear 5 and with it the rotary grinding 35 head 7.

In order to provide proper lubrication for the relatively rotating parts the stud shaft 11 preferably is provided with a central duct 27 having communicating apertures 28 leading 40 to the surface of said shaft, said apertures being positioned at desirable intervals within the hub of the gear 21.

An oil port 29, leading to the socket 13 for the end of the stud shaft 11, provides 45 means for supplying oil to the duct 27. A port 30 also may lead from the thrust bearing at the end of the shaft 6 into the socket 13, whereby oil introduced into the socket 13 will serve to lubricate the bearing of the 50 beveled gear 21 and also the thrust bearing of the shaft 6. The shaft 6 may also be provided with a central vertical oil duct 31 having a lateral port for lubricating the journal of said shaft which lies within the 55 downwardly extending boss 8, said duct being supplied by a usual grease cup or reservoir.

The lower end of the journal within the boss 8 desirably is provided with a gland 32 60 which will prevent the escape of oil at the lower end of said journal. A semi-cylindrical casing 33 secured to the casing member 9 is provided to inclose the gears 9 and 25 and a disk-like cover 34 having a central 65 offset portion 34^x to cover the beveled gear

21 serves to complete the closure of the gear casing so that dust will be excluded from the gears.

The rotary grinding head 7 may be of the character disclosed in my prior application 70 aforesaid of which this constitutes a division and preferably comprises three grinding tools 35 disposed in triangular relation, each of said grinding tools being connected by a universal joint 36 to the rotary grinding head or plate 7. The grinding tools 35 desirably are composed of three abrasive grinding members located in triangular relation to one another. By this construction an equal amount of pressure will be applied to each abrasive member, for the triangular relation of the tools with their universal connections to the driving head causes each tool to sustain its one third of the weight imposed upon the grinding head 85 irrespective of the unevenness of the base upon which the grinding tools rest and each of the abrasive members of each tool for a like reason supports its proportionate share of the weight imposed upon the grinding 90 tool of which it forms a part.

It will be noted that the platform is supported so that the weight of the motor will bear upon the grinding tools with a uniform pressure, notwithstanding the unevenness of 95 the surface upon which the machine is operated, by reason of the fact that the platform is supported at its front end upon the rotary grinding tool and at its rear end by wheels 37, 38 disposed in triangular relation 100 to the rotary grinding wheel.

The wheels 37, 38 are mounted upon an axle 39 which is carried by a frame comprising arms 40, 41 which are pivotally secured to a shaft 42 mounted in the casing 4. The 105 arms 40, 41 are connected by a cross piece 43 to maintain the same in parallelism and to provide a rigid frame therefor.

The axle 39 is adjustably secured to the platform by a pair of locking racks 44 having teeth 45, 46 adapted to engage the axle 39. The racks 44 are connected to a shaft 47 carried by brackets 48 depending from the under face of the platform 1. One of the racks 44 is provided with an integral 110 offset lever 49 adapted to be depressed by the foot of the operator to disengage the racks 44 from the axle 39. The racks 44 however are normally maintained in engagement with the axle by a helical spring 115 50 surrounding the shaft 47 and secured at one end to one of said racks and at its opposite end engaging the under face of the platform. In order to prevent complete disengagement of the racks 44 from the axle 39 and consequently the dropping of the platform I have found it convenient to provide the racks with integral keepers 51 which will permit the racks to be shifted so that their teeth may engage the axle 120 125 130

but which will prevent the entire disengagement of said racks and the consequent dropping of the rear end of the platform.

A suitable handle 52 is connected to the platform by brackets 53, 54 which may be secured together by bolts 55 to form a rigid structure. A switch located upon the handle within easy reach of the operator may conveniently be provided for the purpose of controlling the motor, the usual conductors leading to said switch from a suitable source of power and from said switch to the motor.

In order to prevent the rotary grinding member from coming in contact with the walls or other vertical surfaces a guard 56 is provided which is in the form of a metallic ring preferably extending entirely around the grinding head and supported by brackets 57 from the casting which forms 20 the platform and gear casing as above described.

In the operation of the machine the rotation of the motor shaft 26 drives the rotary grinding head in the manner above described. The greater part of the weight of the motor rests upon the grinding head and causes the abrasive members to engage the surface being ground or polished more firmly than is usual in machines heretofore constructed. This engagement during the rotation of the rotary driving head causes the machine to move forward and by reason of the fact that the opposite end of the platform which carries the motor is supported upon wheels the tool is readily moved over the surface being treated. As a matter of fact the rotation of the grinding member will ordinarily cause the machine to progress at about the right speed and it is only necessary to guide the same by the handle. By virtue of the short base length between the rotary grinding tool and the wheels which support the opposite end of the platform a compact construction is provided which will permit the grinding tool to work well into the corners of the room.

The lower end of the shaft 6 is provided with an angular enlarged section 58 having a central hemispherical extension 59. The 50 rotary grinding head 7 is provided centrally with a socket having an angular portion 60 to receive the angular portion 58 of the shaft and also with a hemispherical socket 61 to receive the extension 59 of said shaft.

In the operation of the machine the hemispherical extension serves to maintain the proper centering of the shaft in the rotary grinding head while the angular portion 60 causes proper engagement between the shaft and driving head to cause rotation of the latter.

By reason of the short base of the machine the operator can, by pressing upon 65 the handle, raise the front end of the ma-

chine about the wheel base as a fulcrum so as to disengage the end 58 of the shaft 6 from its engagement with the socket in the rotary driving head in order that wheels of different size or of different character may 70 be substituted, thereby adapting the machine readily to any class of work which it is desired to perform.

The rotary grinding head 7 may be equipped with brushes or with other types 75 of tools to perform scouring, buffing or other special kinds of work so that the machine is capable of adaptation for various uses with the mere substitution of one tool for another.

It is to be understood that the embodiment of the invention disclosed herein is illustrative but not restrictive and that various modifications in construction and arrangement of parts may be made within the 85 meaning and scope of the following claims.

Having thus described my invention what I claim as new and desire to secure by Letters Patent is:

1. In a machine of the class described 90 comprising a rotary grinding head having abrasive means connected thereto, a truck having two wheels, a platform carried by said wheels and said rotary grinding head, a motor located upon said platform, said 95 wheels and grinding head being arranged to form a triangular support for said motor, the motor being carried mainly by said rotary grinding head, said grinding head having a vertical shaft journaled in bearings in said platform beneath said motor, a gear on said vertical shaft and a system of gearing positioned to transmit power from the shaft of the motor to the gear upon the vertical shaft.

2. In a machine of the class described 105 comprising a rotary grinding head having abrasive means connected thereto, a truck having two wheels, a platform carried by said wheels and said rotary grinding head, 110 a motor located upon said platform, said wheels and grinding head being arranged to form a triangular support for said motor, the motor being carried mainly by said rotary grinding head, said grinding head having a vertical shaft, provided with an angular head engaging a complementary socket in said grinding head, journaled in bearings in said platform and gearing connecting the shaft of the motor with said vertical shaft.

3. In a machine of the class described 120 comprising a rotary grinding head having a vertical shaft and provided with abrasive members, a platform, a motor supported by said platform over said grinding head, said platform comprising offset portions providing a gear casing and a journal for the shaft of said rotary grinding head, a cover for said gear casing having a thrust bearing for the shaft of said rotary grinding head, a stud 130

shaft having one end mounted in said cover and supported at its opposite end by said gear casing, and gears upon said stud shaft engaging respectively the gears upon the shaft of the motor and upon the shaft of the rotary grinding head.

4. In a machine of the class described comprising a motor, a rotary grinding head having abrasive means connected thereto, a train of gears operating to drive said grinding head from said motor, a platform supporting the said motor having offset portions forming a casing for said train of gears, a cover for said gear casing having means for receiving the adjacent ends of the shafts of said gears, the opposite ends of said shafts being mounted in said gear casing.

5. In a machine of the class described comprising a platform, a motor on said platform, a truck supporting the rear end of said platform, a rotary grinding head having abrasive means connected thereto and having a vertical shaft journaled in said platform beneath said motor supporting the front end of said platform, a horizontal stud shaft removably secured in said platform, gears on said motor shaft and the vertical shaft of said grinding head, and reducing gears mounted upon said stud shaft engaging respectively the gears upon said motor shaft and the gears upon said vertical shaft.

6. In a machine of the class described comprising a platform, a motor on said platform, a truck supporting the rear end of said platform, a rotary grinding head having abrasive means connected thereto and

having a vertical shaft journaled in said platform beneath said motor supporting the front end of said platform, a horizontal stud shaft removably secured in said platform, gears on said motor shaft and the vertical shaft of said grinding head, reducing gears mounted upon said stud shaft engaging respectively the gears upon said motor shaft and the gears upon said vertical shaft, an axial duct in said stud shaft having ports leading to the surface thereof within said reducing gears, and means for supplying lubricant to said duct.

7. In a machine of the class described comprising a platform, a motor on said platform, a truck supporting the rear end of said platform, a rotary grinding head having abrasive means connected thereto and having a vertical shaft journaled in said platform beneath said motor supporting the front end of said platform, a horizontal stud shaft removably secured in said platform, gears on said motor shaft and the vertical shaft of said grinding head, reducing gears mounted upon said stud shaft engaging respectively the gears upon said motor shaft and the gears upon said vertical shaft, an axial duct in said stud shaft having ports leading to its surface within said reducing gears, means for supplying lubricant to said duct, and a duct leading from said lubricant supplying means to the journal of said vertical shaft.

In testimony whereof I have signed my name to this specification.

ERCOLE CAVICCHI.
